UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING MACHINE

Application filed June 18, 1923, Serial No. 646,001. Renewed September 15, 1930.

My invention relates to mining machines and more particularly to mining machines of the flexibly fed type.

An object of my invention is to provide an improved mining machine. Another object of my invention is to provide improved mining machine feeding means including feed operating and take-up mechanisms on the machine. A further object of my invention is to provide a compact low machine especially adapted for low vein work. A still further object of my invention is to provide an improved mining machine readily adaptable to either the longwall or room and pillar method of mining. These and other objects and advantages of my invention will hereinafter more fully appear.

In the accompanying drawings I have shown two forms which my invention may 20 assume in practice.

In these drawings,—

Fig. 1 is a plan view, partially in section, of a mining machine, arranged to make a longwall cut, incorporating my improved 25 mechanism.

Fig. 2 is a side elevation of Fig. 1.

Fig. 3 is a plan view of the machine shown in Fig. 1 arranged to make a room and pillar cut.

30 Fig. 4 is a side elevation of the rear end of the machine.

Fig. 5 is a side elevation of the opposite rear end of the machine.

Figs. 6, 7 and 8 are diagrammatic views 35 of the machine arranged to make a longwall cut.

Fig. 9 is a diagrammatic view of the machine arranged to make a room and pillar cut.

40 Figs. 10, 11 and 12 are views corresponding to Figs. 1, 2 and 5 but showing a modified construction.

In the illustrative form of my invention shown in Figs. 1 to 9 inclusive, I have shown 45 my invention applied to an air propelled, flexibly fed, mining machine adapted to slide on its bottom 1 on the mine bottom relative to a flexible feeding means of any suitable form preferably adapted to provide advance and receding portions, herein in the form of

a chain 4, and carrying at one end a pivoted cutter bar 2.

Referring more particularly to the machine, it will be noted that the same herein comprises a motor section 5, a feed section 6, and a cutter carrying section 7, all being 55 slideable on the mine bottom and the feed and the cutter carrying sections being disposed at opposite ends of the motor section 5 and rigidly connected to the latter. As shown, it 60 will also be noted that the feed and motor sections slide directly on their own bottoms while the cutter section has a suitable shoe underlying the same. Of these sections, the motor section has disposed therein a fluid 65 pressure actuated motor of any approved form, herein transversely disposed and comprising a pair of intermeshing toothed rotors 8 and 9 disposed in bores 10 and 10', respectively, formed in the motor section 5 and 70 rotatable on transverse axes lying in the same parallel planes and suitably secured to shafts 11 and 12 journaled in heads 13 and 14 forming a portion of the side walls of the machine frame. Fluid pressure is admitted 75 to the motor in a well known manner through a connection 15 from any suitable source of supply. It is obvious that the heads 13 and 14 may be detached from the motor casing to permit removal of the motor rotors laterally 80 from the machine frame without detaching the feed and cutter frame sections from the motor section. It will clearly be understood that this form of motor is shown for purposes of illustration only and that motors other 85 than the air propelled type may be used advantageously.

Operatively associated with the rotors 8 and 9 is the cutting mechanism including the cutter bar which carries a cutter chain 16 90 suitably driven from one of the rotors. More particularly, it will be noted that a spur pinion 17 is herein suitably secured to the shaft 12 of the rotor 9 which meshes with a reach gear 18 which in turn meshes with a gear 19 95 disposed on a transversely disposed horizontal shaft 19' journaled in the frame section 7. Splined to the shaft 19' is a jaw clutch 20 operated by a lever 20' adapted to connect the gear 19 to the shaft. Secured 100

to the shaft 19' is also a worm 21 which meshes with a worm gear 22 journaled on a vertical shaft 23 coaxial with the pivot of the cutter bar 2, which rotates the cutter chain 16 in a well known manner through connections not shown. Also driven by the gear 19 is a pinion 24 which meshes with a gear 24' disposed on a shaft 25 arranged parallel with the shaft 19'. The shaft 25 has a pinion 26 secured thereto which meshes with an intermediate gear 27 which in turn meshes with a gear 28 journaled on the shaft 19' and is adapted to be connected thereto by means of a jaw clutch 29 operated by a lever 29' to drive the worm and consequently the cutter chain 16 in an opposite direction. The frame section 7 is also herein provided with a circular flange 30 having a plurality of radially located apertures 31 formed therein in which a pin 32 likewise receivable in the bar is insertable to lock the cutter bar in operative position in a well known manner. The cutter bar 2 is herein also as usual provided with a projection 33 to which the chain 4 is attached to swing the cutter bar about its pivot in a well known manner. From the foregoing it is clearly evident that the cutter bar may be swung about its pivot to either side of the machine and locked in position and that the cutter chain may be rotated in opposite directions, as circumstances require, by means of the jaw clutches 20 and 29. Here it should also be noted that a removable swing arm supported sprocket 33' may be inserted in one of the unused apertures in the flange 30 for purposes hereinafter described (see Fig. 3).

Referring more particularly to the feed frame section 6 which incorporates my improved feeding mechanism, it will be noted that suitably secured to the rotor shaft 11 is a pinion 34 which meshes with a reach gear 35 journaled in the frame and which in turn meshes with a gear 36 journaled on a sleeve 36' journaled on a transverse horizontal shaft 37. The gear 36 drives the shaft 37 through a friction clutch mechanism, generally designated 38, and reduction gears 39, 40, 41 and 42 at a fast or haulage speed, and through a friction clutch mechanism 43 through reduction gears 39, 40, 44, 45, 46, 47, 48 and 49 at a slow or cutting speed. The friction clutches 38 and 43 are herein under control of a shipper 50 operated by a lever 51 on the rear end of the machine frame. Further, it will be noted that detachably secured to opposite ends of the transverse shaft 37, as by jaw clutches 52 and 53 operated by levers 52' and 53', is a feed operating member 54 and a take-up member 55. From the foregoing description it will be clearly evident that the members 54, 55 may be driven from the motor in one direction at fast or slow speeds simultaneously or independently, and that a variation of these speeds may

be obtained by the varying of the amount of application of the clutches 38 and 43. The members 54, 55 herein also have members 56 and 57, respectively, secured thereto provided with friction surfaces on their exterior periphery with which brake bands 58 and 59 cooperate, these bands being operated by levers 58' and 59' carried by the rear end of the machine frame. Cooperating with the feed operating member 54 and the take-up member 55 is the flexible feeding member or chain 4. Herein with the machine operating as shown in Figs. 1, 2, 5, 6, 7 and 8 to make a longwall cut, it will be noted that the advancing portion of the chain extends from a suitable anchor A at the face, along the face, beneath an idler sprocket 60, then forwardly and upwardly around an idler sprocket 61, beneath the feed operating member 54, and then upwardly and transversely across the top of the machine in a guide channel 62, and then downwardly beneath the take-up member 55, it being understood that the member 55 is released from the shaft 37, the feed chain then passing upward over an idler sprocket 63, the receding portion of the feed chain lying slack on the mine bottom and not necessarily being connected to a jack during the cut along the face. It will be noted that if desired the feed chain may also be arranged to cooperate with the member 55, passing beneath the idler 64 and guide rolls 65, 66, and 67 on the feed frame section and then extend laterally along the face to the jack A.

In the operation of my improved construction when used for longwall cutting, the machine, when unloaded from its transport truck (not shown) or otherwise brought up to a face, is preferably first brought up to a position adjacent the face, as shown in full lines in Fig. 6, with the cutter bar in line with the longitudinal axis of the machine. The chain 4 is first attached to the projection 33 on the cutter bar and by throwing in the jaw clutch 52 and by applying the friction mechanism 43 the cutter bar is swung in under the coal and locked in the desired lateral position by the pin 32. Then the chain 4 is detached from the bar and extended forwardly along the face to an anchor jack A and the clutch 43 is again applied to the feed operating member to cause the latter to draw in one end of the chain at a slow or cutting speed while the take-up member permits the other end to be paid out, the brake band 59 being released at this time and the chain being guided in the channel 62. If an obstruction is encountered, the friction clutch 43 is thrown out and the receding portion of the chain is extended along the machine and around the swing arm supported sprocket 33' to a jack B, as indicated by dotted lines in Fig. 6. The jaw clutch 52 is then thrown out and the clutch 53 thrown in, whereupon

125

130

by applying the friction 43 the receding portion of the chain is drawn in and the advancing portion paid out under control of brake band 58 in such manner as to swing the machine bodily from the face. By extending the chain directly to the jack B, as shown in Fig. 7, the other end of the machine may be swung bodily from the face. Fig. 8 also shows the machine cutting and swinging out at the opposite face, the operation being similar to that shown in Figs. 6 and 7.

Referring more particularly to Figs. 3, 4, 5 and 9 it will be noted that the machine is shown arranged to make a room and pillar cut. In this disposition of parts, it will be noted that the cutter bar is swung in line with the longitudinal axis of the machine and the advancing portion of the chain extended beneath the feed operating member 54, upward over the idler 61, forwardly toward the front of the machine, and then around the swing arm supported sprocket 33' laterally along the face to the rib, while the receding portion extends upwardly from the sprocket 54 and transversely across the top of the machine in the guide channel 62 and then downwardly under the take-up member 55, upwardly and forwardly around the idler 63, downwardly and rearwardly beneath an idler 64, around guiding rolls 65 and 66 and then laterally to the opposite rib. Obviously by reversing the arrangement of the feed chain 3 the machine may cut from left to right.

In the operation of my improved construction when used for room and pillar cutting, the machine when unloaded from its truck (not shown) is preferably first brought up to a position adjacent the face shown in full lines in Fig. 9 and the advancing portion of the chain 4 is then attached to a jack A at the left hand rib, while the receding portion is attached to a jack B at the right hand rib. The motor is then started and the cutter chain clutch thrown in to actuate the cutter chain. The jaw clutch 52 is then thrown out and the jaw clutch 53 thrown in whereupon by applying the friction clutch 43 the bar is sumped in under the coal, the take-up member 55 drawing in the chain at a slow feed while the feed operating member slowly pays it out under control of brake band 58. After sumping, the jaw clutch 53 is thrown out and the clutch 52 is thrown in and by then applying the friction 43 the machine is straightened up and caused to cut transversely across the face at a cutting speed, its position during that cut being indicated in dotted lines. When the machine reaches the end of its transverse cut, it is angled and backed out in a well known manner. Further, by applying the friction 38 the machine may be drawn around the mine at a fast or haulage speed. A sprocket 55', shown in Fig. 1 may also be detachably secured to the take-up member 55 to drive its transport

truck, in a well known manner. Obviously, when the machine is cutting in the opposite direction the truck driver sprocket may be removed or transposed to the opposite side of the machine.

From the foregoing, it will be seen that this form of my invention provides a machine having feed operating and take-up members thereon which is adapted for either the long-wall or room and pillar method of mining and one which is capable of cutting in either direction and at a speed which is subject to considerable variation and which may be readily controlled, said machine also having provision whereby it is made capable of furnishing power to propel its transport truck about the mine. It will also be seen that this wide adaptability of the machine is obtained by means of relatively simple and compact feeding mechanism.

In Figs. 10, 11 and 12 I have illustrated a modified construction, my invention being shown therein as applied to a room and pillar machine. In this construction it will be noted that an electric motor 67 is disposed transversely of the front end of the machine frame, the motor being over the cutter bar 68 as usual in room and pillar machines, and that driving connections are provided between this motor and a feeding mechanism, similar to that previously described, and between the motor and a cutter chain driving sprocket 69 located beneath the rear of the machine and driving a cutter chain 70 on the bar 68. Referring more specifically to these connections, it will be noted that herein the motor armature shaft carries a single pinion 71 meshing with an intermediate spur gear 72 suitably journaled on a transverse axis in the frame and in turn meshing with a like spur gear 73 keyed to a transverse shaft 74 disposed between the motor and the feeding mechanism previously mentioned. As illustrated, this shaft 74 is journaled at its opposite ends in the opposite sides of the frame and carries a plurality of bevel pinions 75, 76 adapted to cooperate selectively with an upstanding bevel gear 77 operatively connected to the cutter chain driving sprocket 69, the direction of rotation of the latter depending upon the position of a clutch member 78 splined to the shaft and having clutch teeth on opposite ends adapted to engage the members 75, 76. Thus it will be evident when the position of the member 78 is adjusted by a suitable clutch controlling mechanism 79, it is possible to drive or disconnect the cutter chain 70 whenever desired or to rotate the cutter chain in different directions without reversing the direction of the motor. Operatively connected to the shaft 74 so as to be driven thereby when desired and whether the cutting mechanism is operating or thrown out of operation, is the feeding mechanism previously mentioned. In this construction it

will be noted that a pinion 80 is keyed to the shaft 74 and meshes directly with the fast feed gear 36 of the feeding mechanism. It will also be noted that the opposite end of the shaft carries pinions 81 and 82 and a larger spur gear 83 meshing respectively with the gears 46, 47, 49 of the slow feed mechanism, the pinion 81 being fixed to the shaft and driving the remainder of the gears to effect a slow speed drive of the shaft 37.

In the operation of this construction it will be evident that the same will be substantially like that described in connection with Fig. 9, and that, except as made necessary by the differences indicated, the feeding mechanism common to the two forms of my invention will operate in a generally similar manner and be similarly controlled. It will also be evident that with such a construction it is made possible to operate the feeding and cutting mechanism in opposite directions without reversing the motor, the feeding mechanism being reversely operative by reversing the arrangement of the flexible feeding means while the cutting mechanism is reversely operative by changing the connection of the clutch shipper 78. In order to enable this reverse operation, this machine is ordinarily provided with a transposable front guide 84 corresponding to the guide 33' previously described. It will also be observed that as a result of the possibility of employing a motor constantly rotating in the same direction, it is made possible to eliminate any necessity for the provision of a reversible motor or reversing mechanism therefor, the motor being capable of being controlled through a simple stopping and starting controller indicated at 85. Attention is also directed to the fact that inasmuch as the motor may operate continuously at full speed when desired, i. e. not only during cutting but during unloading, loading, and transport, it is made possible not only to eliminate the difficulties arising from making and breaking of circuit connections and thereby render the machine more safe for use in gaseous mines, but also to simplify the controlling mechanism. These and other advantages of my improved construction will, however, be clearly apparent to those skilled in the art.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining machine, a motor, cutting mechanism driven thereby including a pivoted cutter bar, feeding mechanism including a feed operating member and a take-up mem-

ber each rotatable on a transverse axis, a shaft rotatable therewith, and means for driving either member including variable speed driving connections between said shaft and motor.

2. In a mining machine, a motor, cutting mechanism driven thereby including a pivoted cutter bar, feeding mechanism including a feed operating member and a take-up member each arranged on a transverse axis, and variable speed connections between each of said members and said motor including means to drive said members simultaneously or independently.

3. A mining machine having reversible cutting mechanism thereon, feeding mechanism thereon including a feed operating member and a take-up member, said members having the same mode of operation in either direction of cutting of said mechanism, a driving motor operatively connected to said members, and mechanism for enabling said machine to cut in opposite directions in accordance with the room and pillar system without reversing said motor.

4. A mining machine having reversible cutting mechanism thereon, feeding mechanism thereon including a feed operating member and a power driven take-up member, both said feed operating and take-up members being rotatable at a similar cutting speed, a driving motor operatively connected to said members, and mechanism including means for reversing said cutting mechanism for enabling said machine to cut in opposite directions in accordance with the room and pillar system without reversing said motor or the direction of rotation of said feed operating and take-up members.

5. A mining machine normally slidable upon a mine bottom having reversible cutting mechanism thereon, feeding mechanism thereon including a feed operating member and a power driven take-up member, both said feed operating and take-up members being rotatable at a plurality of speeds including a cutting speed, a driving motor operatively connected to said members, and mechanism including means for reversing said cutting mechanism for enabling said machine to cut in opposite directions in accordance with the room and pillar system without reversing said motor or the direction of rotation of said feed operating and take-up members.

6. A mining machine normally slidable upon a mine bottom having reversible cutting mechanism thereon, feeding mechanism thereon including a feed operating member and a take-up member, a motor for driving said mechanisms, and mechanism for enabling said machine to cut in opposite directions in accordance with the longwall system without reversing said motor or the direction of rotation of said feed operating and take-up members.

7. A mining machine normally slidable upon a mine bottom having reversible cutting mechanism thereon, feeding mechanism thereon including a feed operating member and a take-up member, a motor for driving said mechanisms, and mechanism for enabling said machine to cut in opposite directions in accordance with the room and pillar system without reversing the direction of rotation of said members during power drive thereof.

8. A mining machine normally slidable upon a mine bottom having reversible cutting mechanism thereon, feeding mechanism thereon including a feed operating member and a take-up member, each adapted to cooperate with flexible feeding means, a motor for driving said mechanisms, and mechanism including means for reversing said cutting mechanism for enabling said machine to cut in opposite directions in accordance with the longwall system of the room and pillar system without reversing said motor or rereeing said flexible feeding means relative to said members.

9. A mining machine normally slidable upon a mine bottom comprising reversible cutting mechanism including a pivoted cutter bar, feeding mechanism including a feed operating member and a take-up member, a motor for driving said members, mechanism for driving said cutting mechanism in opposite directions without reversing said motor, and means for feeding said machine in either direction during cutting in accordance with the longwall system without reversing said motor or the direction of rotation of said feed operating and take-up members.

10. A mining machine normally slidable upon a mine bottom comprising reversible cutting mechanism including a pivoted cutter bar, feeding mechanism including a feed operating member rotatable on a horizontal axis, a motor, mechanism for driving said cutting mechanism in opposite directions without reversing said motor, a flexible feeding member cooperating with said feed operating member, and means for feeding said machine in opposite directions during cutting in accordance with the longwall system without reversing said feed operating member or changing the arrangement of said flexible member on said feed operating member.

11. A mining machine normally slidable upon a mine bottom comprising reversible cutting mechanism including a pivoted cutter bar, feeding mechanism including a feed operating member rotatable on a horizontal axis, a motor, mechanism for driving said cutting mechanism in opposite directions without reversing said motor, a flexible feeding member cooperating with said feed operating member, and means for feeding said machine in opposite directions during cutting in accordance with the longwall system

without reversing said motor or said feed operating member or changing the arrangement of said flexible member on said feed operating member.

12. A mining machine comprising reversible cutting mechanism including a pivoted cutter bar, feeding mechanism including a feed operating member rotatable on a horizontal axis, a motor, mechanism for driving said cutting mechanism in opposite directions without reversing said motor, a flexible feeding member cooperating with said feed operating member, and means for feeding said machine in opposite directions during cutting in accordance with the longwall system without reversing said feed operating member or changing the arrangement of said flexible member on said feed operating member.

13. A mining machine comprising reversible cutting mechanism including a pivoted cutter bar, feeding mechanism including a feed operating member rotatable on a horizontal axis, a motor, mechanism for driving said cutting mechanism in opposite directions without reversing said motor, a flexible feeding member cooperating with said feed operating member, and means for feeding said machine in opposite directions during cutting in accordance with the longwall system without reversing said motor or said feed operating member or changing the arrangement of said flexible member on said feed operating member, said means likewise having provision for rotating said feed operating member at a plurality of speeds in the same direction.

14. A mining machine comprising reversible cutting mechanism including a pivoted cutter bar, feeding mechanism including a feed operating member and a take-up member, a motor, mechanism for driving said cutting mechanism in opposite directions without reversing said motor, a flexible feeding member cooperating with said feed operating member and take-up member, and means for feeding said machine in opposite directions during cutting in accordance with the longwall system without reversing said motor or said feed operating and take-up members.

15. A mining machine comprising reversible cutting mechanism including a pivoted cutter bar, feeding mechanism including a feed operating member and a take-up member, a motor, mechanism for driving said cutting mechanism in opposite directions without reversing said motor, a flexible feeding member cooperating with said feed operating member and a take-up member, and means for feeding said machine in opposite directions during cutting in accordance with the longwall system without reversing said motor or said feed operating or take-up members or changing the arrangement of said

flexible member relative to one of the same.

16. In a mining machine, a frame slidable on its bottom on the mine bottom during cutting and having thereon a motor disposed on an axis disposed transversely of the machine, cutting mechanism including a pivoted cutter bar, means for driving the same from said motor, feeding mechanism, and means to drive said feeding mechanism at variable speeds from said motor, said mechanisms being driven from the same end of said motor.

17. In a mining machine, a motor disposed on an axis extending transversely of the machine, cutting mechanism including a cutter bar, means for driving the same from said motor, feeding mechanism including a rotatable feed operating member and a rotatable take-up member and cooperating flexible feeding portions, one adapted to be wound in by each member, and positively operable means driven by said motor adapted to rotate either member to wind in at a plurality of speeds.

18. In a mining machine, a transversely disposed motor, cutting mechanism including a cutter bar, means for driving the same from said motor, feeding mechanism including a rotatable feed operating member and a rotatable take-up member and cooperating flexible feeding portions, one adapted to be wound in each member, and positively operable means driven by said motor adapted to rotate either member to wind in at a plurality of predetermined speeds.

19. In a mining machine, a transversely disposed motor, cutting mechanism driven thereby, a feed operating member, a take-up member, a single continuous flexible feeding member cooperating with both of said members having free end portions adapted to be drawn in by different members relative thereto, and means driven by said motor adapted to actuate either member to wind in either portion at variable speeds.

20. In a mining machine, a machine frame slidable on the mine bottom during the cutting operation, cutting mechanism having a power shaft disposed at one end of said machine, feeding mechanism at the opposite end thereof, and a transversely disposed motor arranged between said feeding mechanism and shaft and operatively connected to each of the same, said mechanisms being driven from the same end of said motor.

21. In a mining machine, cutting mechanism including a pivoted cutter bar, feeding mechanism including a feed operating member and a take-up, and a transversely disposed motor arranged between said mechanisms and operatively connectible to said cutting mechanism and either of said members.

22. In a mining machine, a motor having a plurality of intermeshing rotors, reversible cutting mechanism, and means whereby the latter is always driven directly from the same

rotor during either direction of operation thereof.

23. In a mining machine, a motor having a plurality of intermeshing rotors, feeding mechanism driven directly from only one of said rotors, and reversible cutting mechanism driven in either direction directly from only another of said rotors.

24. In a mining machine, a motor having a plurality of rotors, cutting mechanism driven directly from only one of said rotors, feeding mechanism driven directly from only another of said rotors, and reversing mechanism for one of said mechanisms disposed between the latter and its respective driving rotor.

25. In a mining machine, a motor having a plurality of rotors, cutting mechanism driven directly from only one of said rotors, feeding mechanism driven directly from only another of said rotors, and reversing mechanism for said cutting mechanism disposed between the latter and its respective driving rotor, said reversing mechanism including a plurality of power transmission parallel shafts.

26. In a mining machine, cutting and feeding mechanisms, said feeding mechanism including a feed operating member adapted to cooperate directly with flexible feeding means, a transverse motor, and means extending in opposite directions directly from opposite sides of said motor whereby said mechanisms may be driven thereby.

27. In a mining machine, feeding and cutting mechanisms, a transverse motor, and means extending directly from opposite sides of said motor in opposite directions and from only one end thereof for driving said mechanisms.

28. In a mining machine, a transverse motor having a plurality of rotors, cutting mechanism and feeding mechanism on opposite sides thereof, and means for operatively connecting different mechanisms to different rotors.

29. In a mining machine, a transverse motor having a plurality of rotors, cutting mechanism and feeding mechanism on opposite sides thereof, and means for operatively connecting different mechanisms to the same end of different rotors.

30. In a mining machine, a motor, cutting mechanism driven thereby, and feed mechanism driven by said motor including a transverse shaft, a feed operating member, a take-up member, said members being arranged coaxially with said shaft, means to connect the same directly to said shaft, and friction means for simultaneously or separately controlling said members when released from said shaft.

31. In a mining machine, a motor, feeding mechanism driven thereby including a transverse shaft, means to drive said shaft from

73

75

80

115

120

125

130

said motor at a plurality of predetermined speeds, means to vary said speeds, a feed operating member, a take-up member, said members being arranged coaxially with said shaft, and means to releasably connect the same to said shaft for driving thereby.

32. In a mining machine, a motor, feeding mechanism driven thereby including fast and slow speed gearing, a transverse shaft driven thereby, friction means to vary the speed of said shaft, a feed operating member and a take-up member, said members being arranged coaxially with said shaft, means to connect said members to said shaft for driving thereby, and friction means to simultaneously or separately control said members when released therefrom from said shaft.

33. In a mining machine, a transversely disposed fluid actuated motor, reversible cutting mechanism, feeding mechanism including a feed operating member and a take-up member, each of said members having the same mode of operation during either operation of said cutting mechanism, flexible feeding means cooperating with said members, and means to drive said cutting mechanism and the machine during cutting in either direction without reversing said motor.

34. In a mining machine, a reversible cutting mechanism, and means for driving the same including a worm and worm gear, and means having opposite directions of rotation for driving said worm from opposite ends thereof to effect drive of said cutting mechanism in opposite directions.

35. In a mining machine, a reversible cutting mechanism and means for driving the same including a worm and worm gear, means for driving said worm from opposite ends thereof, and reversibly moving mechanism for said cutting mechanism disposed on each end of the driving means for said worm to effect drive of said cutting mechanism in opposite directions.

36. In a mining machine, a reversible cutting mechanism, means for driving the same including a transversely disposed shaft, a worm thereon, a worm gear meshing therewith, and means having opposite directions of rotation for driving said shaft at opposite ends of said worm to effect drive of said cutting mechanism in opposite directions.

37. In a mining machine, a reversible cutting mechanism, a shaft directly connected to said mechanism for actuating the same, a worm gear carried by said shaft, a worm for driving said gear, and means having opposite directions of rotation for driving said worm from opposite ends thereof to effect drive of said cutting mechanism in opposite directions.

38. In a mining machine, feeding mechanism including coaxial feed operating and take-up members disposed at the same end of

the machine, and means for driving said members at high and low speeds, said means including high and low speed clutches coaxial with said members.

39. In a mining machine, coaxial feed operating and take-up members, means for driving said members at high and low speeds, said means including high and low speed friction clutches coaxial with said members, and a clutch disposed between said friction clutches and each of said members.

40. In a mining machine, feeding means therefor including a transversely disposed shaft, feed operating and take-up members carried thereby, and means for driving said members at predetermined fast and slow speeds including friction clutches disposed coaxially with said shaft.

41. In a mining machine, feeding means therefor including a transversely disposed shaft, feed operating and take-up members carried thereby, and means for driving said members selectively at predetermined fast and slow speeds including friction clutches disposed coaxially with said shaft.

42. In a mining machine, feeding means therefor including a transversely disposed shaft, feed operating and take-up members carried thereby, and means for driving said members at predetermined fast and slow speeds in the same direction including friction clutches disposed coaxially with said shaft.

43. In a mining machine, a reversible cutting mechanism, and feeding mechanism therefor including feed operating and take-up members adapted to be rotated by power in the same direction to feed said machine in either lateral direction during cutting, and reversing gearing associated with said cutting mechanism to effect drive of the latter in opposite directions.

44. In a mining machine, a frame disposable on the mine bottom comprised of three sections consisting of a feed section, a motor section, and a cutter carrying section, the motor section being interposed between said feed and cutter carrying sections and rigidly secured thereto, a horizontal rotor element housed in said motor section and having its axis disposed transversely of the machine, and means permitting the removal of said rotor element longitudinally from the side of said motor section while said sections retain their operative rigid relation.

45. In a mining machine, a motor, cutting mechanism driven by said motor, and feeding mechanism driven by said motor including parallel shafts rotatable on horizontal axes extending transversely of the machine, a feed operating member and a take-up member disposed coaxially with one of said shafts, and means for driving said members at a plurality of speeds including intermeshing gearing carried by said shafts, certain of

- said gears being arranged coaxially with said members, and clutches for alternatively connecting said coaxial gears directly to said shaft.
46. In a mining machine, a motor, cutting mechanism driven by said motor, and feeding mechanism driven by said motor including parallel shafts rotatable on horizontal axes extending transversely of the machine, a feed operating member and a take-up member disposed coaxially with one of said shafts, means for driving said members at a plurality of speeds including intermeshing gearing carried by said shafts, certain of said gears being arranged coaxially with said members, clutches for alternatively connecting said latter gears directly to said coaxial shaft, and means for independently or simultaneously connecting said members to said coaxial shaft.
47. In a mining machine, a motor, cutting mechanism driven by said motor, and feeding mechanism driven by said motor including a shaft rotatable on an axis extending transversely of the machine, a feed operating member and a take-up member arranged coaxially with said shaft, and means for driving said members at a plurality of speeds including a fast speed gear train and a slow speed gear train, a gear of each train being disposed coaxially with said shaft, and clutches for alternatively connecting said coaxial gears to said shaft.
48. In a mining machine, a motor, cutting mechanism driven by said motor, and feeding mechanism driven by said motor including a shaft rotatable on an axis extending transversely of the machine, a feed operating member and a take-up member arranged coaxially with said shaft, and means for driving said members at a plurality of speeds including a fast speed gear train and a slow speed gear train, a gear of each train being disposed coaxially with said shaft, clutches for alternatively connecting said coaxial gears to said shaft, means for simultaneously or independently connecting said members to said shaft, and means for frictionally controlling said members when released from said shaft.
49. In a mining machine, a motor, cutting mechanism driven thereby, and feeding mechanism driven by said motor including coaxially disposed feed operating and take-up members rotatable on an axis extending transversely of the machine, and transmission means including fast and slow speed gearing between said members and said motor, all of the gearing of said transmission means being disposed on axes parallel to a line parallel with said first axis.
50. In a mining machine, a motor, cutting mechanism driven thereby, and feeding mechanism for the machine including coaxially arranged feed operating and control-
- ling members disposed at the same end of the machine and rotatable on axes parallel to a line parallel with the motor axis and adapted to cooperate with flexible feeding means, and a plural speed driving mechanism between said motor and members including a fast speed clutch and a slow speed clutch disposed coaxially with said members.
51. In a mining machine, a motor, cutting mechanism driven thereby, and feeding mechanism including a plurality of feed operating and controlling members disposed at the same end of the machine and rotatable on axes parallel to a line parallel with the motor axis and adapted to cooperate with flexible feeding means, and a plural speed driving mechanism between said motor and members including a fast speed clutch and a slow speed clutch disposed coaxially with said members.
52. In a mining machine, a motor, cutting mechanism driven thereby including a pivoted cutter bar, feeding mechanism including a feed operating member and a takeup member arranged on a transverse axis, and variable speed connections between each of said members and said motor including means to drive said members simultaneously or independently and always in the same direction.
53. In a mining machine, a driving motor, means driven thereby for feeding said machine laterally during cutting including fast and slow speed gearing, a transverse shaft driven thereby, friction means to vary the speed of said shaft, a feed operating member and a takeup member, means to simultaneously connect said members to said shaft for rotation therewith, and friction means to control said members when released from said shaft.
54. In a mining machine, a driving motor, means driven thereby for feeding said machine laterally during cutting including fast and slow speed gearing, a transverse shaft driven thereby, friction means to vary the speed of said shaft, a feed operating member and a takeup member, means to either selectively or simultaneously connect said members to said shaft for rotation therewith, and friction means to control said members when released from said shaft.
55. In a mining machine of the type slideable on its bottom on the mine bottom during its operation, a driving motor, feeding mechanism driven thereby for feeding the machine bodily laterally over the mine bottom during cutting including a transversely disposed shaft, means to drive said shaft from said motor at a plurality of predetermined speeds, means to vary said speeds, a feed operating member and a take-up member each adapted to cooperate with flexible feeding means, and means to releasably connect said members to said shaft for driving thereby.
56. In a mining machine of the type slide-

ble on its bottom on the mine bottom during its operation, a driving motor, feeding mechanism driven thereby for feeding the machine bodily laterally over the mine bottom during cutting including fast and slow speed gearing, a transverse shaft driven thereby, frictional means to vary the speed of said shaft, a feed operating member and a take-up member each adapted to cooperate with flexible feeding means, means to releasably connect said members to said shaft for driving thereby, and frictional means to control said members when released from said shaft.

57. In a mining machine of the type slideable on its bottom on the mine bottom during its operation, a motor, cutting mechanism driven by said motor including a horizontally projecting cutter bar, and feeding mechanism driven by said motor for feeding the machine bodily laterally over the mine bottom during cutting including a shaft disposed transversely of the machine, and fast and slow speed friction operating clutches arranged coaxially with said shaft.

58. In a mining machine of the type slideable on its bottom on the mine bottom during its operation, a motor, cutting mechanism driven by said motor including a horizontally projecting cutter bar, and feeding mechanism driven by said motor for feeding the machine bodily laterally over the mine bottom during cutting including a transversely disposed horizontal shaft, a feed operating member and a take-up member disposed coaxially with said shaft and each adapted to cooperate with flexible feeding means, and fast and slow speed friction operating clutches for said members arranged coaxially with said shaft.

59. In a mining machine of the type slideable on its bottom on the mine bottom during its operation, a motor, cutting mechanism driven by said motor including a horizontally projecting cutter bar, and feeding mechanism driven by said motor for feeding the machine bodily laterally over the mine bottom during cutting including a horizontal shaft, feed operating and take-up members arranged coaxially with said shaft and each adapted to cooperate with flexible feeding means, fast and slow speed friction clutches arranged coaxially with said shaft for controlling said members, and controlling clutches interposed between said members and said clutches.

60. In a mining machine, the combination with a main frame adapted to rest upon and slide in any direction over the mine bottom, of an elongated kerf cutter projecting forwardly lengthwise of said frame during cutting, a plurality of rotatable feed operating members mounted upon said frame with their axes extending transversely thereof, power devices upon the frame, and control mechanism adapted to connect said feed operating members with said power devices to cause said members to revolve in winding direction

either simultaneously or separately at relatively high speed or at a relatively low speed and a clutch mechanism for each feed operating member and adapted to connect said members separately or simultaneously with said power devices and to permit rotation of said feed operating members independently of each other.

61. In a mining machine, the combination with a main frame adapted to rest upon and slide in any direction over a mine bottom, of an elongated rigid kerf cutter projecting longitudinally of said frame during cutting, a plurality of feed operating members mounted on said frame with their axes extending transversely thereof and adapted to cooperate with flexible feeding means, power devices on said frame, control mechanism adapted to connect said feed operating members with said power devices to cause said members to revolve in winding direction either simultaneously or separately at relatively high speed or at relatively low speed or to permit them to revolve in the upwinding direction under frictionally controlled resistance, and means to control the actuation of each of said members independently of each other.

62. In a mining machine, the combination with a main frame adapted to rest upon and slide in any direction over a mine bottom, of an elongated rigid kerf cutter projecting longitudinally of said frame during cutting, a plurality of feed operating members mounted on said frame with their axes extending transversely thereof and adapted to cooperate with flexible feeding means, power devices on said frame, control mechanism adapted to connect said feed operating members with said power devices to cause said members to revolve in winding direction either simultaneously or separately at relatively high speed or at relatively low speed or to permit them to revolve in the unwinding direction under frictionally controlled resistance, or to permit them to revolve in unwinding direction without such resistance, and means to control the actuation of said members independently of each other.

63. In a mining machine of the type slideable on its bottom on the mine bottom, a driving motor, feeding mechanism for feeding the machine bodily laterally over the mine bottom during cutting driven by said motor and disposed at the rear of said motor including a transversely disposed shaft, means to drive said shaft from said motor at a plurality of predetermined speeds, means to vary said speeds, a feed operating member and a take-up member each adapted to cooperate with flexible feeding means, and means to releasably connect said members to said shaft.

64. In a mining machine, a machine frame including a motor casing slideable directly on its bottom on the mine bottom, said casing

housing a motor having a horizontal power shaft, the height of the motor substantially determining the height of the machine, reversible cutting mechanism driven from one end of said motor including a forwardly projecting cutter bar, and feeding mechanism driven from the same end of said motor and adapted to feed the machine over the mine bottom during cutting in either direction, including relatively rotatable feed operating members driven by said motor and each adapted to cooperate with flexible feeding means.

65. In a mining machine, a machine frame 15 slidable on its bottom on the mine bottom, a motor carried thereby, feeding and cutting mechanisms driven by said motor and disposed respectively at the opposite ends of said frame, said motor being located between 20 said mechanisms and said cutting mechanism including a pivoted cutter bar swingable into different positions relative to said frame, said feeding mechanism including a plurality of relatively rotatable feed operating 25 members driven by said motor and rotatable on horizontal axes extending transversely of the machine and each adapted to cooperate with flexible feeding means.

66. The combination with a mining machine 30 slidable on a mine bottom and flexible feeding means therefor operative to feed the same transversely of a mine face during cutting and including advance and receding flexible feeding portions and relatively rotatable feed operating members cooperating respectively with said portions, of actuating mechanism for said feeding means including a plurality of sets of driving elements each adapted to produce a different feeding speed, 40 a shaft on which one of the elements of each of said sets is mounted, and different friction clutches for connecting one of said last mentioned elements to said shaft.

67. In a mining machine of the type 45 slidable on its bottom on the mine bottom during its operation, feeding mechanism including flexible feeding means including a plurality of flexible feeding portions, feed operating members respectively cooperating with said portions, and driving and controlling means for said relatively rotatable feed operating members including a plurality of drive trains having coaxial terminal elements rotating at different speeds, a shaft on which said terminal 55 elements are rotatably mounted, and operative connections between said terminal elements and said feed operating members including clutch means for separately connecting said terminal elements to said shaft and clutch means for selectively effecting driving of said feed operating members by said shaft.

68. In a mining machine, a machine frame 60 slidable on its bottom on the mine bottom, a horizontal motor disposed centrally on said

frame and having a forwardly located motor pinion and a rearwardly located motor pinion, cutting mechanism disposed at the front end of said frame and driven from said forwardly located motor pinion and including a forwardly projecting cutter bar, and feeding means disposed at the rear end of said frame and driven from said rearwardly located motor pinion for feeding the machine bodily laterally over the mine bottom during cutting comprising a plurality of relatively rotatable feed operating members each adapted to be driven by power from said motor and disposed at the end of said frame remote from that from which said cutter bar projects, and cooperating flexible feeding means including separate advance and receding flexible feeding elements extending in opposite directions from opposite ends of said frame and cooperating with said feed operating members respectively, said advance feeding element having its free end anchored at a point in advance of the advancing side of the machine and said receding feeding element having its free end anchored at a point in the rear of the receding side of the machine, said feed operating members being operable to independently draw in said flexible portions by power.

69. In a mining machine capable of cutting in opposite directions, a substantially horizontal motor having a casing disposable directly on the mine bottom, said motor casing substantially determining the height of said machine, reversible cutting mechanism driven by said motor including a transversely disposed cuttings discharge channel and a horizontal plane cutter bar whose top and bottom surfaces lie in planes intersecting said motor, and feeding mechanism including a plurality of coaxial relatively rotatable winding members driven by said motor.

70. In a mining machine capable of cutting in opposite directions, a substantially horizontal motor slidable directly on its bottom on the mine bottom, the height of the motor substantially determining the height of said machine, reversible cutting mechanism driven by said motor including a rigid horizontal plane cutter bar whose top and bottom plane surfaces lie in planes intersecting said motor and a transversely disposed cuttings discharge channel, and feeding mechanism including a plurality of coaxial transversely disposed relatively rotatable winding members driven by said motor.

71. In a mining machine, a substantially horizontal motor slidable directly on its bottom on the mine bottom, cutting mechanism driven by said motor and including a horizontal plane cutter bar disposed in planes which intersect said motor, feeding mechanism including a feed member and a take-up member driven by said motor and driving mechanism for said members and cutting

mechanism, and means to disconnect said cutting mechanism and said members from said driving mechanism.

72. In a mining machine, a motor having a frame housing power producing means providing a surface slidably engageable with the mine bottom during cutting, the vertical dimension of said frame being substantially only that requisite to the power producing function of the motor, feeding mechanism including a feed operating member and a take-up member each operatively connected to said motor, and means to speed up or slow down said members without disconnecting them from the motor.

73. The combination in a mining machine capable of cutting in opposite directions, of an elongated machine frame slideable on its bottom on the mine bottom, reversible cutting mechanism including a cutter carrying bar projecting from one end of said frame, feeding mechanism including a feed operating member rotatable on a transverse axis at one side of said frame and adjacent the front end thereof, and a relatively rotatable take-up member, cooperating flexible feeding means including flexible feeding members cooperating with said feed operating and take-up members, and guiding means on said frame cooperating with said flexible members and directing the same laterally from opposite ends of said frame.

74. The combination in a mining machine slideable on its bottom on the mine bottom, of cutting mechanism including a cutter chain carrying cutter bar projecting at one end of the machine, and a cooperating cutter chain driving element, of feeding and guiding mechanism operative to feed said machine along a face when said bar projects into the face, said mechanism including a feed operating member rotatable during cutting along the face of an axis parallel to the face and the plane of said bar, and a relatively rotatable take-up member, flexible feeding means comprising an advance flexible feeding portion cooperating with said feed operating member and disposable in a single strand connection to a fixed point in juxtaposition to the face and in advance of the machine, a receding flexible portion cooperating with said take-up member and disposable to a fixed point in rear of the machine, and guiding means for said advance flexible portion including a guiding member so disposed relative to said feed operating member and so cooperating with the advance flexible portion between the feed operating member and its point of fixation as to direct the advance portion along the face to its point of fixation substantially in a plane parallel to and adjacent the face and including the point from which the bar projects, and of a horizontal motor operatively connected to said cutter chain driving element and said feed operating and

take-up members, said motor being so disposed and all of said previously mentioned elements being so disposed within the vertical limits of the motor that the height of the machine is substantially the height of said motor.

75. In a mining machine of the class described, the combination with a main frame adapted to rest upon and slide in any direction over the mine floor, of an elongated kerf cutter projecting from said frame, two winding elements mounted upon said frame with their axes extending transversely thereof, power devices upon the frame, clutch mechanism adapted to connect said elements with said power devices to cause said elements to revolve in winding direction either simultaneously or separately at relatively high speed or at relatively low speed or to permit them to revolve in the unwinding direction under frictionally controlled resistance, and means to control the actuation of each of said elements independently of each other as and for the purpose set forth.

76. In a mining machine of the class described, the combination with a main frame adapted to rest upon and slide in any direction over the mine floor, of an elongated kerf cutter projecting from said frame, two winding elements mounted upon said frame with their axes extending transversely thereof, power devices upon the frame, and clutch mechanism adapted to connect said elements with said power devices to cause said elements to revolve in the winding direction either simultaneously or separately at relatively high speed or at relatively low speed, to permit them to revolve in the opposite direction under frictionally controlled resistance or to permit them to revolve in the unwinding direction without such resistance as and for the purpose set forth.

77. In a mining machine, a machine frame slideable on its bottom on the mine bottom, a motor carried by said frame, cutting mechanism driven by said motor, and feeding means driven by said motor including relatively rotatable winding members disposed on horizontal axes extending transversely of the machine and each adapted to cooperate directly with flexible feeding means and mechanism for effecting rotation of said winding members in winding direction either simultaneously or separately at relatively high speed or at relatively low speed while said cutting mechanism is driven by the motor at a substantially uniform rate, or to permit rotation of said members in unwinding direction under frictionally controlled resistance, or to permit rotation of said members in unwinding direction without such resistance.

78. In a mining machine, a machine frame slideable on its bottom on the mine bottom, a motor carried by said frame, cutting mechanism driven by said motor, and feeding

means driven by said motor including relatively rotatable winding members disposed on horizontal axes extending transversely of the machine and each adapted to cooperate directly with flexible feeding means, and mechanism for effecting rotation of said winding members in winding direction either simultaneously or separately at relatively high speed or at relatively low speed while said cutting mechanism is driven by the motor at a substantially uniform rate, or to permit rotation of said members in unwinding direction under frictionally controlled resistance.

79. In a mining machine, feeding mechanism including coaxial feed operating and take-up members rotating on axes lying in a line extending transversely of the machine, and means for driving said members at high and low speeds, said means including jaw and friction clutches disposed coaxially with said feed operating and take-up members.

80. In a mining machine of the class described, the combination with a main frame adapted to rest upon and slide in any direction over the mine floor, of an elongated kerf cutter projecting from said frame, two winding elements mounted upon said frame with their axes extending transversely thereof, power devices upon the frame, and mechanism for connecting said elements with said power devices to cause said elements to revolve in winding direction either simultaneously or separately at relatively high speed or at relatively low speed, said mechanism including a shaft extending transversely of the main frame and coaxial with the winding elements and jaw and friction clutch devices coaxial with said shaft.

81. In a mining machine of the class described, the combination with a main frame adapted to rest upon and slide in any direction over the mine floor, of an elongated kerf cutter projecting from said frame and including a cutter chain, two winding elements mounted upon said frame with their axes extending transversely thereof, a motor upon the frame, driving connections between the motor and cutter chain, and mechanism for connecting said elements with said motor to cause said elements to revolve in winding direction either simultaneously or separately at relatively high speed or at relatively low speed while the cutter chain is driven by the motor at a substantially uniform rate, or to permit them to revolve in unwinding direction under frictionally controlled resistance or freely, said mechanism including a shaft extending transversely of the main frame and coaxial with the winding elements and jaw and friction clutch devices coaxial with said shaft.

82. In a mining machine of the class described, the combination with a main frame adapted to rest upon and slide in any direc-

tion over the mine floor, of an elongated kerf cutter projecting from said frame, two winding elements mounted upon said frame with their axes extending transversely thereof, power devices upon the frame, and mechanism for connecting said elements with said power devices to cause said elements to revolve in winding direction either simultaneously or separately at relatively high speed or at relatively low speed, or to permit them to revolve in unwinding direction under frictionally controlled resistance or freely, said mechanism including a shaft extending transversely of the main frame and coaxial with the winding elements and jaw and friction clutch devices coaxial with said shaft, said jaw clutch mechanisms arranged to transmit to said winding elements frictionally controlled power from said power devices.

83. In a mining machine of the class described, the combination with a main frame adapted to rest upon and slide in any direction over the mine floor, of an elongated kerf cutter projecting from said frame, two winding elements mounted upon said frame with their axes parallel to a transverse vertical plane, power devices upon the frame, clutch mechanism adapted to connect said elements with said power devices to cause said elements to revolve in winding direction either simultaneously or separately at relatively high speed or at relatively low speed or to permit them to revolve in the unwinding direction under frictionally controlled resistance, and means to control the actuation of each of said elements independently of each other as and for the purpose set forth.

84. In a mining machine of the class described, the combination with a main frame adapted to rest upon and slide in any direction over the mine floor, of an elongated kerf cutter projecting from said frame, two winding elements mounted upon said frame with their axes parallel to a transverse vertical plane, power devices upon the frame, and clutch mechanism adapted to connect said elements with said power devices to cause said elements to revolve in the winding direction either simultaneously or separately at relatively high speed or at relatively low speed to permit them to revolve in the opposite direction under frictionally controlled resistance or to permit them to revolve in the unwinding direction without such resistance as and for the purpose set forth.

85. In a mining machine of the class described, the combination with a main frame adapted to rest upon and slide in any direction over the mine floor, of an elongated kerf cutter projecting from said frame, two winding elements mounted upon said frame at the opposite sides of the longitudinal vertical center thereof with their axes parallel to a transverse vertical plane, one on the advanc-

ing side of the machine and the other on the receding side thereof, power devices upon the frame, clutch mechanism adapted to connect said elements with said power devices to cause said elements to revolve in winding direction either simultaneously or separately at relatively high speed or at relatively low speed or to permit them to revolve in the winding direction under frictionally controlled resistance, and means to control the actuation of each of said elements independently of each other as and for the purpose set forth.

86. In a mining machine of the class described, the combination with a main frame adapted to rest upon and slide in any direction over the mine floor, of an elongated kerf cutter projecting from said frame, two winding elements mounted upon said frame at the opposite sides of the longitudinal vertical center thereof with their axes parallel to a transverse vertical plane, one on the advancing side of the machine and the other on the receding side thereof, power devices upon the frame, and clutch mechanism adapted to connect said elements with said power devices to cause said elements to revolve in the winding direction either simultaneously or separately at relatively high speed or at relatively low speed to permit them to revolve in the opposite direction under frictionally controlled resistance or to permit them to revolve in the unwinding direction without such resistance as and for the purpose set forth.

87. In a mining machine, an elongated machine frame slidable on its bottom directly on the mine bottom during cutting and comprising a front cutting section, a motor section and a rear feed section, said motor section being interposed between said cutting and feed sections and resting directly on the mine bottom, the vertical dimension of said motor section being substantially only that requisite to the power producing function of the motor and substantially determining the height of the machine, a horizontal motor disposed in said motor section, kerf cutting mechanism driven by said motor including a horizontal cutter bar projecting forwardly from the machine frame, and feeding mechanism driven by said motor including relatively rotatable feed operating and take-up members carried by said feed section and independently rotatable by power and flexible feeding means cooperating with said members respectively.

88. In a mining machine, an elongated machine frame slidable on its bottom directly on the mine bottom during cutting comprising a front cutting section, a motor section and a rear feed section, said motor section being interposed between said cutting and feed sections, a horizontal motor disposed in said motor section, kerf cutting

mechanism driven by said motor including a horizontal cutter bar projecting forwardly from the machine frame, and feeding means driven by said motor including relatively rotatable feed operating and take-up members carried by said feed section and independently rotatable by power, one of said members being disposed on the advancing side and the other of said members being disposed on the receding side thereof, and advance and receding flexible feeding portions cooperating with said members respectively and extending in opposite directions from opposite ends of the machine frame.

89. In a mining machine, an elongated machine frame slidable on its bottom directly on the mine bottom during cutting comprising a front cutting section, a motor section and a rear feed section, said motor section being interposed between said cutting and feed sections, a horizontal motor disposed in said motor section, kerf cutting mechanism driven by said motor including a horizontal cutter bar projecting forwardly from the machine frame, and feeding means driven by said motor including relatively rotatable feed operating and take-up members arranged on said feed section with their axes parallel to a transverse vertical plane and independently rotatable by power, and flexible feeding means cooperating with said members respectively and extending in opposite directions from opposite ends of the machine frame.

90. In a mining machine, an elongated machine frame slidable on its bottom directly on the mine bottom during cutting comprising a front cutting section, a motor section and a rear feed section, said motor section being interposed between said cutting and feed sections, a horizontal motor disposed in said motor section, kerf cutting mechanism driven by said motor including a horizontal cutter bar projecting forwardly from the machine frame, and feeding means driven by said motor including relatively rotatable feed operating and take-up members carried by said feed section and disposed on horizontal axes and independently rotatable by power, and flexible feeding means cooperating with said members respectively and extending in opposite directions from opposite ends of the machine frame.

91. In a mining machine, an elongated machine frame slidable on its bottom directly on the mine bottom during cutting comprising a front cutting section, a motor section and a rear feed section, said motor section being interposed between said cutting and feed sections, a horizontal motor disposed in said motor section, kerf cutting mechanism driven by said motor including a horizontal cutter bar projecting forwardly from the machine frame, and feeding means driven by said motor including relatively rotatable feed

operating and take-up members carried by said feed section and disposed on horizontal axes extending transversely of the machine frame, one on the advancing side of the machine and the other on the receding side thereof, said members being independently rotatable by power, and advance and receding flexible feeding portions engaging said members respectively and extending in opposite directions from opposite ends of the machine frame.

92. In a combined room and pillar and longwall mining machine, an elongated machine frame slidable on its bottom directly on the mine bottom during cutting and comprising a cutting section, a motor section and a feed section, said motor section being interposed between said cutting and feed sections, a horizontal motor disposed in said motor section, cutting mechanism driven by said motor including a horizontally swingable cutter bar pivoted on said cutter section, and feeding means driven by said motor including relatively rotatable feed operating and take-up members carried by said feed section, one of said members being disposed on the advancing side of the machine and the other on the receding side thereof, said members being independently rotatable by power, and flexible feeding means cooperating with said members respectively.

93. In a combined room and pillar and longwall mining machine, an elongated machine frame slidable on its bottom directly on the mine bottom during cutting and comprising a cutting section, a motor section and a feed section, said motor section being interposed between said cutting and feed sections and resting directly on the mine bottom, the vertical dimension of said motor section being substantially only that requisite to the power producing function of the motor and substantially determining the height of the machine, a horizontal motor disposed in said motor section, cutting mechanism driven by said motor including a horizontally swingable cutter bar pivoted on said cutter section, the top and bottom surfaces of said cutter bar lying in planes intersecting said motor section, and feeding means driven by said motor including relatively rotatable feed operating and take-up members carried by said feed section and independently rotatable by power, and flexible feeding means cooperating with said members respectively.

55 In testimony whereof I affix my signature.
CHARLES F. OSGOOD.

CERTIFICATE OF CORRECTION.

Patent No. 1,804,946.

Granted May 12, 1931, to

CHARLES F. OSGOOD.

It is hereby certified that error appears in the printed specification of the above numbered patent requiring correction as follows: Page 3, line 64, after "Fig. 1" insert a comma; page 5, line 22, claim 8, for "of" read or; page 9, line 89, claim 61, for "upwinding" read unwinding; page 11, line 43, claim 74, for "of" read on; and that the said Letters Patent should be read with these corrections therein that the same may conform to the record of the case in the Patent Office.

Signed and sealed this 6th day of October, A. D. 1931.

(Seal)

**M. J. Moore,
Acting Commissioner of Patents.**
